UNITED STATES PATENT OFFICE.

HENRY BAETZ, OF ST. LOUIS, MISSOURI.

VENTILATING APPARATUS.

Original application filed May 5, 1920, Serial No. 379,072. Divided and this application filed June 10, 1921. Serial No. 476,556.

To all whom it may concern:

Be it known that I, HENRY BAETZ, a citizen of the United States, residing at St. Louis, State of Missouri, have invented 55
5 certain new and useful Improvements in Ventilating Apparatus, of which the following is a specification.

The present invention is directed to improvements in ventilating apparatus and is 60
10 a division of my application on ventilation filed May 5, 1920, Serial No. 379,072, patented March 25, 1924, No. 1,488,225. The object primarily sought is to introduce fresh air into the room to be ventilated in such 65
15 a manner as to enable the occupants to inhale and be surrounded by air which has not come in contact with the walls, floor or ceiling. A further object is to temper the outside air before discharging the same into 70
20 the room, but not heating it to a higher degree than nature subjects it to, in order that the person breathing the air may obtain the same refreshing and invigorating effect as would be obtained outdoors when 75
25 the temperature is between 65 and 70 degrees. A further object is to deliver into the room fresh outside air warmed or tempered to various degrees that harmonize with the different degrees existing between 80
30 the floor and ceiling of the room. This last object is attained by recognizing the presence of more or less defined zones of temperature in a heated room undergoing ventilation, and tempering the incoming air to harmonize with these zones. For example, an 85
35 average room temperature of about 70 degrees Fahrenheit is considered comfortable, and when a thermometer which is hung about five feet above the floor registers that 90
40 degree, the bodily comfort of the occupant is amply provided for. In this room it will be found that near the ceiling the thermometer will register considerably higher, probably 90 degrees, while at the floor it 95
45 will be lower than 70 degrees and probably close to 60 or even 50 degrees. This, of course, is due to the natural law that the warmer air rises while the cooler air falls. There thus exist between the floor and ceiling 100
50 zones of different temperature, these zones being in the form of horizontal strata which, while not sharply defined, may have

their limits located with reasonable accuracy by means of a thermometer. Further and other advantages will be better apparent from a detailed description of the accompanying drawings in which—

Figure 1 represents a vertical section through the outer wall and window of a room showing in side elevation one form of temperature apparatus for giving effect to my ventilating system; Fig. 2 is an enlarged top plan of the apparatus with parts broken away; Fig. 3 is an enlarged front elevation with parts broken away; Fig. 4 65
is a side elevation of Fig. 3 with motor removed, and parts of the casing walls broken away; Fig. 5 is an enlarged horizontal sectional detail on the line 5—5 of Fig. 4; and Fig. 6 is an enlarged horizontal 70
sectional detail on the line 6—6 of Fig. 4.

Referring to the drawings, 1 represents a casing made preferably in two sections, the bottom section being provided with a blower or fan 2 operated preferably by an electric motor M positioned adjacent to one of the side walls of the casing, the opposite side wall being tapped by an air intake pipe P which admits outside air to the fan 2 as well understood in the art. Disposed between the side walls of the upper section of the casing is a transverse partition wall 3 extending a substantial distance along the height of the casing, said partition wall dividing the casing into two contiguous compartments, to-wit, a cold air compartment 4 at the back of the casing, and a hot air compartment 5 at the front of the casing, both compartments being in free communication with the mixing chamber 5' from which the air is discharged through the outlet opening O into the room to be ventilated. The compartment 5 is provided with steam circulating coils 6 connecting the feed and drain headers 7, 8, respectively, said headers preferably tapping the front wall of the casing, the rotation of the fan 2 maintaining a constant pressure of air in the hot and cold air compartments. Disposed across the casing adjacent to the front wall thereof and immediately over the heating coils is a box 9 the bottom of which is provided with two air nozzles 10, 10', for delivering jets

of air from the compartment 5 into the chamber of the box, the said nozzles being controlled by valves or dampers 11, 11', respectively one of the nozzles being closed 5 while the other is open, the air jets discharging alternately first through one nozzle and then the other for a purpose which will hereinafter more fully appear. The valves 11, 11' are secured to the free end of the 10 lower bent arm of a vertically oscillating lever 12 fulcrumed about a pin 13 on a bracket or hanger 14 depending from the roof of the box 9, the upper arm of the lever operating through an elongated slot s 15 in said roof and terminating at its upper end in a weight or ball 15. Supported by the hanger 14 at a point below the fulcrum of the lever 12 is the inner end of an air motor shaft 16, the opposite end 20 passing through and outside the casing wall and beyond the outer supporting bearing 17 of the shaft, the end of the shaft projecting beyond the bearing 17 being provided with a worm pinion 18 meshing with 25 a worm gear 19 at the adjacent end of a countershaft 20 mounted in the brackets 21, 21 projecting from the side wall of the casing 1. Disposed at an intermediate point of the shaft 20 is a worm 22 which 30 is in mesh with the teeth of an oscillating sector or quadrant 23 secured to the outer projecting end of a transversely disposed rock-shaft 24, disposed along the inner bottom corner of the box 9. The rock-shaft 35 24 serves as a hinge pin for the damper 25 which extends across the casing 1 and is free to oscillate between the inner vertical wall of the box 9 and the partition 3, the said damper when in vertical position 40 projecting somewhat above the box 9 (Fig. 4) to facilitate the mixing of the hot and cold air. The free edge of the damper 25 is provided at the center with a pair of ears or lugs h to which is pivotally coupled 45 the adjacent end of a link 26, the opposite end of the link being pivotally secured to a corresponding pair of ears or lugs h' at the free edge of a second damper 27 hinged in any suitable manner along the inside of 50 the rear wall of the casing 1 so that one damper moves with the other.

Secured to, or formed integrally with the upper arm of the lever 12, and opening toward the lever, is a yoke 28, the arms of 55 which have mounted thereon adjustable tappets or screws 29, 29' respectively, adapted to be alternately engaged or struck by the long arm of a bell-crank lever 30 pivoted at the bottom of a frame or mounting 31 60 secured to the casing 1 adjacent to the outlet opening O, the bell-crank lever being controlled and actuated in one direction by a spring 32 having its ends secured to the long lever arm and frame respectively, the 65 bottom of the frame being provided with a

slot t for the free play of the short arm of the bell crank, the free end of said arm permanently engaging (under the action of the spring 32) the lower end of the stem 33 of any conventional thermostatic member 70 34 secured in the mounting 31, the air passing in contact with this thermostatic member just before it enters the room. The shaft 16 carries a wheel or air motor W which is practically in continuous motion, 75 being actuated first in one direction and then the other by the air jets discharging alternately through the nozzles or openings 10 and 10', (the valves being actuated by the thermostat) said nozzles being disposed 80 on opposite sides of the rotation axis of the air motor wheel to effect reverse rotations thereof as stated. The air accumulating in the box 9 escapes through a grating G in the front wall of the casing 1 85 which likewise forms the front wall of the box 9. The air in the room is heated to proper temperature by a steam or hot water radiator R, or other means, the vitiated air in the main escaping through the grating 90 V of a foul air flue (not shown). The pipe P is coupled to an elbow P' leading from an air-box B which is inserted under a raised window sash A for admitting outside air into the pipe and casing 1, the box B 95 extending the full width of the sash so that no untempered outside air shall be allowed to enter the room. Preferably, the tempering apparatus is supported on a bracket D as shown in Fig. 1. 100

The operation of the apparatus is as follows: Having determined on the maximum and minimum temperature of the air discharged into the room, and assuming them to be 75 and 65 degrees respectively, the tap-pet 29 is so adjusted that at 65 degrees the thermostat's (34) position has permitted the spring 32 to pull the long arm of the lever 30 in proper direction to cause the said arm to oscillate the shifting lever 12 to one side (to the left) of its neutral vertical position or dead center, the weight 15 throwing the lever to its position of rest as shown (Fig. 4). This final throw uncovers the nozzle 10 and covers the nozzle 10' with the valve or shutter 11' on the lower end of the shifting lever. The air jet which escapes through the open nozzle 10 impinges against the paddles of the air motor wheel W and causes it to revolve, thereby setting in motion the dampers 25 and 27 through the gear connections 18, 19, 20, 22 and 23, and rock-shaft 24, as previously described. The direction in which the dampers 25 and 27 110 are now moving (to the left Fig. 4), causes a gradual, progressive increase of the flow of heated air from heating chamber 5 into the mixing chamber 5', and at the same time a corresponding progressive decrease of the cold air, resulting in a mixture of air at 115 120 125 130

steadily increasing temperature, which after mixing contacts with the thermostat 34 and enters the room. The tappet 29' is next adjusted so that when the temperature of the mixed air has gradually risen to 75 degrees and caused the expansion of the thermostat to move the bell crank, it will move the shifting lever 12 back and past the dead center so that the weight will cause it to drop to 10 its opposite position of rest as shown by the dotted line α (Fig. 4). The nozzle 10' is now uncovered while nozzle 10 is closed, causing a reversal of the air motor and a reverse movement of the dampers, which 15 progressively decreases the quantity of heated air flowing into the mixing chamber 5' and correspondingly increases the flow of cold air into said chamber, resulting in a flow of air with progressively decreasing 20 temperatures which contacts with the thermostat and enters the room. When the temperature has fallen to 65 degrees the thermostat again permits the spring 32 to throw the shifting lever, and this oscillation 25 of the temperature of the air continues. It is obvious that because the thermostat controls the reversal of the air motor it will maintain these limits of temperature whether the outside temperature rises or falls so 30 that the temperature of the air which enters the room is both regulated and oscillated.

The period of time consumed between the shifting of the lever 12 may be regulated by the flow of air permitted through the nozzles 35 10, 10'. A greater quantity will turn the air motor faster and a lesser quantity slower, the size of the nozzles being determined by trial.

Having described my invention, I claim:

40 1. In a ventilating system, a tempering apparatus comprising a casing provided with air intake and discharge openings, hot air and cold air compartments for heating and tempering the air discharged from the casing, dampers for controlling the air discharged from the respective compartments, an air motor, valve-controlled jet nozzles leading from the hot air compartment for actuating the motor in either direction, intermediate gear connections between the motor and dampers aforesaid for actuating the dampers, and thermostatically controlled means for actuating the jet-controlling valves in proper direction to effect reversals of the motor and corresponding tempering of the air discharged from the casing.

45 2. In a ventilating system, a tempering apparatus comprising a base provided with air intake and discharge openings, hot air and cold air compartments for heating and tempering the air discharged from the casing, dampers for controlling the air discharged from the respective compartments, a motor, valve controlled jet nozzles dis-

posed on opposite sides of the rotation axis of the motor leading from the hot air compartment for actuating the motor in either direction, intermediate gear connections between the motor and dampers aforesaid for 70 actuating the dampers with a rotation of the motor, a vertically oscillating shifting lever mounted in proximity to the motor, valves carried by the lever and operating across the jet openings aforesaid, the valves 75 being so spaced that the closing of one jet opening leaves the opposite opening uncovered, and a thermostatically controlled member for actuating the shifting lever first in one direction and then the other to effect 80 reversals in the rotation of the motor and a corresponding tempering of the air discharged from the casing.

3. In a ventilating system, a tempering apparatus comprising a casing, hot and cold 85 air compartments therefor, dampers for controlling the air from said compartments, a vertically rotating reversible air motor, jet nozzles leading from the hot air compartment and disposed on opposite sides of 90 the rotation axis of the motor for actuating the latter in either direction, intermediate gearing between the fan and dampers aforesaid, a vertically oscillating weighted lever fulcrumed at an intermediate point opposite 95 the motor, valves on the bottom lever-arm of the lever operating across the passage-ways of the nozzles and spaced to close one nozzle while the other nozzle is uncovered, a yoke secured to the upper lever arm, adjustable tappets on the yoke arms, a spring-controlled bell crank lever having one arm oscillating between the tappets of the yoke, and a thermostat for controlling the bell crank and causing oscillation 100 thereof in one direction or the other depending on the temperature by which the thermostat is affected.

4. In a ventilating system, a tempering apparatus comprising a casing provided 105 with air intake and discharge openings, hot air and cold air compartments for heating and tempering the air discharged from the casing, dampers for controlling the air from the respective compartments, a reversible 110 air motor in the casing, means for directing jets of air from the hot air compartment against the motor to operate the same, valves for controlling said jets to cause the latter to impart rotation to the motor in either direction, thermostatically controlled 115 means for actuating said valves, and intermediate gear connections on the outside of the casing interposed between the motor shaft and the dampers aforesaid.

5. In a ventilating apparatus, a casing provided with intake and discharge openings for the air, means for heating the air, means for tempering the heated air by a proper complement of cold air prior to its 130

discharge into the room, a valve-controlled reversible air motor actuated by the currents from the casing, dampers for controlling the air determining the degree to which
5 the heated air shall be tempered, thermostatically controlled means for actuating the valves controlling the air to the motor, and

intermediate gearing on the outside of the casing interposed between the air motor and the dampers aforesaid.

10

In testimony whereof I hereunto affix my signature.

HENRY BAETZ.
